(57) **CLAIM**

The ornamental design for a multi-head sprayer, as shown and described.

DESCRIPTION

FIG. 1 is a top, front and right side perspective view of a multi-head sprayer showing my new design;
FIG. 2 is a bottom, rear and left side perspective view thereof,

FIG. 3 is a front view thereof,

FIG. 4 is a rear view thereof,

FIG. 5 is a left side view thereof;

FIG. 6 is a right side view thereof;

FIG. 7 is a top view thereof; and,

FIG. 8 is a bottom view thereof.

The broken lines in the figures illustrate the portions of the multi-head sprayer that form no part of the claimed design.
